UNITED STATES PATENT OFFICE

2,427,039

MAIL BOX

Paul J. Arnett, South Charleston, W. Va.

Application June 28, 1946, Serial No. 680,027

3 Claims. (Cl. 232—19)

1. This invention relates to mail boxes.

An object of the invention is to provide a mail box which may be placed in a door such as a storm door and the like by removing one of the glass lights in the door and fastening the mail box in its place.

Another object of the invention is to provide a mail box which may be fastened to a storm door and the like and from which mail may be collected by the residents of a building without opening the storm door, thus providing additional convenience in cold and otherwise disagreeable weather.

A further object of the invention is to provide a mail box which is constructed of a light material such as plastic, and adapted for installation either permanently or temporarily as desired, in doors, with provision for removal of mail therefrom by a resident remaining within the building, with resultant privacy and protection against the elements.

Still another object of the invention is to provide a mail box having the features above mentioned and which is simple in design, inexpensive to manufacture, and effective in operation.

Other objects and advantages of the invention will become apparent from the following description of a preferred embodiment thereof as illustrated in the accompanying drawings, and in which,

Figure 1 is a perspective view of my improved mail box as installed in a door,

Figure 2 is an elevational view of my mail box and the door panel in which it is installed,

Figure 3 is a side elevation in section taken on line 3—3 of Figure 2,

Figure 4 is a rear elevation as seen from the right side of Figure 3,

Figure 5 is a detail perspective of a fastening clamp, and

Figure 6 is a fragmentary sectional elevation of a modified form of mail box.

Reference is now had to the drawings, in which like reference characters denote similar parts throughout the several views. As is shown, the mail box includes a panel 1 formed of plastic material and shaped to fit in the space formerly occupied by a light of glass in the door, the shape being rectangular in the view shown. The panel 1 has an aperture also substantially rectangular in shape, to the edges of which is moulded a standard size plastic mail box 6 having raised molded letters 5. A hinged plastic top or lid 4 for depositing mail swings upward

as shown in Figure 3 by means of plastic circular lugs 2 and 30 and metal pivot pins 3.

Mail is removed from the rear of the box or inside of the house by a plastic door 16, shown in Figures 3 and 4, which is hinged at the bottom on plastic circular lugs 19 and 32 and metal pins 20 and swings downward as shown. In closed position the door 16 is flush with the back face of panel 1 and rests against two plastic lug stops 23, and is held closed by plastic button or handle 13 which is pivoted at its center on pivot pin 14. To open the door, button 13 is turned to a horizontal position and plastic handle 12 is grasped and pulled forward toward the person operating the door. The procedure is reversed upon closing the door. Figures 3 and 4 show the door 16 closed, and Figure 3 also shows the door in partially open position in dotted lines.

20 Attached to the main removal door 16 is a curved piece of thin spring steel 10 with a rolled serrated edge 24, the member 10 being attached to the door by metal rivets 11. The purpose of this curved piece of spring steel is to provide a theft guard or foil by means of which mail may be deposited from the outside but cannot be removed from the outside by persons inserting their fingers through lid 4 to remove the mail. This member 10 also provides protection from rain water should the lid be partly open, and when the door 16 is fully open will also act as a support rest for mail.

At the bottom of the mail box 6 are attached two plastic semi-circular lugs 7 molded into the box and having open holes 8 for the attachment of the conventional type of wire newspaper rack 22, or the like. The plastic panel 1 is scored to a depth of $\frac{1}{8}$ inch at all four corners at quarter inch intervals as at 21. The purpose of this marking is to provide index guides for cutting the panel to size with a knife or fine saw to fit any size standard glass opening of storm or house door.

45 The mail box is installed by removing one of the existing glass lights from the door, trimming panel 1 to size by means of the index markings 21 and attaching removable slotted angle clamps 15 on the inside face of the door mutins 9. These 50 metal clamps 15 as shown best in Figure 5, have a slot 22 which is slid under the head of the fastening screw 26 attached to the door mutins 9. By tightening the screw 26 the panel 1 is held in place and by loosening the screw, the clamp 15 may be slid out for removal of the

panel. The number of removable clamps 15 will vary with the size of the mail box panel 1.

The mail box 6 and panel 1 together with the inside door 16 may all be made of transparent plastic, or various combinations of opaque and transparent plastic. Thus, the mail box 6 and panel 1 may be opaque and the inside door 16 may be transparent, or only door 16 may be transparent if desired. It is advantageous to keep door 16 transparent in order to see at a glance whether mail has been delivered.

Figure 3 shows a removable thin perforated plastic floor 18 with drain holes 17 in the mail box 6, this arrangement being also shown in Figure 2. The purpose of this floor is to give the mail a dry resting place and at the same time remove moisture collecting through condensation or infiltration of rain. Accumulated water collects in the space 25 and is drained off through holes 17. Figure 6 shows a modified construction in which the bottom door 16 is on the same level as the perforated floor 18a, which is molded integral with the box 6 forming the water space 25a beneath.

The main advantage of the mail box shown herein is that the mail can be collected by the residents without opening the storm door since the mail is removed from the rear or inside through the hinged door in the mail box. This mail box is very useful in cold and disagreeable climates, and during cold and bad weather elsewhere during the winter season, since it allows house occupants to collect the mail without getting out into the weather and at the same time prevents the loss of heat from the house. The mail box could be similarly installed in regular house doors. Since many houses at present have no front entrance porch, the installation of the mail box in such residences will provide much greater convenience, protection from the weather, and privacy than is possible in the conventional type of mail box. The mail box is designed to be quickly installed or removed from the door, and can be manufactured to sell as a removable unit in the above manner or permanently installed in storm doors.

Although I have described a preferred embodiment of my invention in specific terms, it is to be understood that various changes may be made in size, shape, materials and arrangement without departing from the spirit and scope of the invention as claimed.

I claim:

1. A mail box for installation in a door panel of a building door, comprising a hollow box like receptacle for mail and comprising a floor member, left and right side walls, and a front wall, 5 a transparent panel member receivable in said door panel and having an aperture therein, said receptacle being molded integral with the marginal edges of said aperture of the panel member, a mail receiving opening in said receptacle, 10 a cover member accessible from outside the door and hinged over said mail receiving opening for closing the same, and a transparent removal door hinged over said panel aperture for permitting persons within the building to remove mail from said receptacle.

2. A mail box for installation in a door panel in a building, comprising a transparent panel member receivable in said door panel and having an aperture therein, a hollow box like mail receptacle molded into said aperture and having an opening outside the door for the reception of mail, 20 said aperture in the panel affording access from inside the building into the mail receptacle for removal of mail therefrom, a hinged lid covering said mail reception opening, and a transparent hinged door for covering said mail removal aperture.

3. A mail box for installation in a door panel in a building, comprising a transparent panel member receivable in said door panel and having an aperture therein, the transparent panel being scored to permit trimming thereof, a hollow box like mail receptacle molded into said aperture and having an opening outside the door for the reception of mail, 30 said aperture in the panel affording access from inside the building into the mail receptacle for removal of mail therefrom, a hinged lid covering said mail reception opening, and a transparent hinged door for covering said mail removal aperture.
